UNITED STATES PATENT OFFICE

2,042,759

VALVE SEAT GRINDING MACHINE

Frans O. Albertson, Sioux City, Iowa, assignor to
 Albertson & Company, Inc., Sioux City, Iowa,
 a corporation of Iowa

Application December 23, 1932, Serial No. 648,564
 Renewed May 11, 1935

11 Claims. (Cl. 51—241)

The present invention relates to valve seat grinding machines particularly adapted for use in the forming, reconstruction or repair of the valve seats of internal combustion engines. 5 However, the methods and apparatus are of general application and may be utilized for valves of different kinds, and I do not wish to be limited in the use of my invention to any particular type of valve.

10 The grinding machines of the prior art either have the grinding stone brought into engagement with the entire periphery of the valve seat at one time or they include complicated devices for both rotating the grinding wheel and revolving 15 the grinding wheel in an orbit to engage all parts of the valve seat with a grinding wheel which is of a smaller diameter. A full seat contact between the grinding wheel and the valve seat results in the clogging or loading of the wheel with the material which is ground from the seat, and this causes a change of the contour of the 20 stone and results in the grooving of the valve seat.

The grinding stones are also apt to be broken when the stone engages the entire periphery at 25 once, and serious injury may result when the grinding stone, which is rotating at a high rate of speed, is broken and its pieces are thrown off from the machine.

The devices of the prior art, which are adapted 30 to revolve the grinding stone in an orbit, as well as rotate the grinding stone, are very complicated and expensive, and such devices cannot be brought within the means of ordinary garage owners on account of the expensive mechanism and machine 35 work required to produce the complicated grinding tool.

One of the objects of the invention is the provision of an improved method of reconstructing valve seats by means of which the extremely 40 hard seats of stellite, tungsten steel, or other hardened alloys can be ground quickly and uniformly to produce a finished seat, with a minimum amount of labor. The tendency in construction of valve seats for internal combustion 45 engines is toward the use of seats of harder material, which cannot be satisfactorily worked by means of ordinary metal cutting tools.

Another object of the invention is the provision 50 of an improved method and apparatus which is adapted to produce a finished valve seat at predetermined angularity, and which is adapted to eliminate the hand-lapping operation which is found necessary when the grinding machines of the prior art are used.

55 Another object of the invention is the provision

of an improved grinding tool by means of which full seat contact is avoided so as to eliminate the clogging and loading of the grinding wheel or grooving of the seat and to provide a grinding tool which is self-cleaning. 5

Another object of the invention is the provision of an improved grinding tool which is adapted to disperse the cuttings continuously and prevent loading of the wheel or filling of the interstices between the abrasive particles of the 10 wheel at the surface with the cuttings, the cuttings being dispersed by the current of air caused by the close proximity of the surface of the abrasive wheel to the valve seat at the points where the wheel does not actually engage the seat. 15

Another object of the invention is the provision of an improved method and apparatus for reconstruction of valve seats by means of which the relatively light stone pressure and the random initial engagement of the stone are adapted to 20 produce a finished seat, the quality of which is commensurate with the quality of a seat secured by a hand-lapping operation.

Another object of the invention is the provision 25 of an improved grinding tool, including a spring for lifting the tool and enabling the operator to use a light stone pressure by means of which the friction on the spring and wheel hub is eliminated so as to prevent the heating of the spring and the drawing of the temper of the spring and 30 to prevent damage to the stone by the heat which melts the sulphur and loosens the stone from its mounting on the hub.

Another object of the invention is the provision 35 of an improved tool holder, an improved dressing tool, an improved motor driver, an improved grinding stone structure, and an improved grinding tool assembly, all of which are simple in construction, sturdy, and capable of manufacture at a low cost, so that the invention may be 40 brought within the means of a vast number of users who may practice the methods disclosed therein with profit to themselves and beneficial results to the valves upon which the tools are used. 45

Another object of the invention is the provision 50 of an improved tool assembly, including a motor driver and a universal connection between the motor driver and a grinding wheel, including means for eliminating the shocks on the grinding wheel which are caused by the introduction of the universal joint in the drive between the motor and wheel so that the present device is adapted to operate more smoothly and uniformly than any of the devices of the prior art to effect 55

a smooth grinding or finishing action on the valve seat and produce a seat which is concentric with the axis of the valve stem guide, and of a predetermined angularity.

5 Another object is the provision of an improved method of dressing the grinding wheel, and an improved dressing apparatus which is adapted to compensate for the divergence in angularity which would be caused by the particular structure and arrangement of the grinding tool without such compensation.

10 Other objects and advantages of the invention will be apparent from the following description and from the accompanying drawings, in which 15 similar characters of reference indicate similar parts throughout the several views.

15 Referring to the drawings, of which there are three sheets,

Fig. 1 is a side elevational view of the grinding 20 apparatus with the valve and valve stem guide in vertical section on a plane passing through the axis of the guide, the assembly including the motor driver, tool holder, grinding wheel and pilot;

25 Fig. 2 is an elevational view of the motor driver in partial section on a vertical plane passing through the axis of the armature shaft and drive shaft, showing the mechanism of the driver;

30 Fig. 3 is a full sized sectional view of the tool holder and grinding wheel and pilot applied to the valve of an internal combustion engine, the section being taken on a vertical plane passing through the axis of the valve stem guide, with 35 the pilot in elevation;

Fig. 4 is a fragmentary view similar to Fig. 3, showing an elevational view of the grinding wheel, with the parts in the proper position for grinding, and showing the angular relation between the frusto-conical surface on the grinding 40 wheel and the valve seat;

45 Fig. 5 is a fragmentary vertical elevational view of the motor driver, tool holder and dressing tool, showing the complete assembly used in the dressing operation;

50 Fig. 6 is a fragmentary elevational view of the grinding wheel, tool holder, pilot and valve seat during the grinding operation, with a diagram to show the angular relations between the position of the grinding wheel during the grinding operation and the dressing operation.

55 The present application relates particularly to the novel elements of the valve seat grinding apparatus, and another co-pending application, Serial No. 643,584, filed November 21, 1932, relates to the method of grinding valve seats.

60 Referring to Fig. 1, the complete assembly of grinding apparatus preferably includes a motor driver 20, a tool holder 21, a grinding wheel 22, and a pilot stem 23.

65 The apparatus is illustrated in connection with a valve seat consisting of a hardened metal ring 24, which has been fixedly secured in the block 25 of an internal combustion engine, which is provided with a valve stem guide 26.

70 The pilot 23 is of the type having a lower cylindrical part 27 which fits the substantially cylindrical part of the valve stem guide 26 very closely, within one one-thousandth of an inch, for the purpose of centering the pilot 23 in the guide.

75 The pilot is also provided with a very gradually tapered wedging portion 28 which extends into the upper part of the valve stem guide 26 and may be fixedly wedged in the guide by merely shoving the pilot downward. The taper is pref-

erably about twenty-three thousandths of an inch per foot, and constitutes the sole means of securing the pilot in place.

Any other type of pilot which is capable of being accurately centered in the valve stem guide 5 26 and fixedly secured therein may be used, such as the expanding pilot covered by my prior Patent No. 1,902,207, issued March 21, 1933.

Referring to Fig. 2, the electric motor driver is shown in detail in this figure. The motor 10 driver preferably consists of an electric motor of the series wound type, having a casing 29 within which is supported, by a plurality of screw bolts 30, the fixed field 31. The upper end of the casing is closed by a cover plate 32 which slidably supports a pair of brushes 33, and which is provided with a socket 34 for receiving the self-aligning ball bearing races 35, 36 and balls 37.

The ball bearings 35-37 are provided with a supply of hard lubricant which is kept in place 20 by an oil seal 38, having a packing 39 engaging the inner race 35.

The armature is fixedly mounted on an armature shaft 40 and provided with appropriate windings, and a commutator 41 and the other 25 end of the armature shaft 40 are mounted in a similar self-aligning bearing comprising races 42, 43, and balls 44 with an oil seal 45 having a packing 46.

The armature has an enlarged portion 47 30 which supports the hub 48 of a fan 49, and the casing is provided with ventilation apertures 50 adjacent the periphery of the fan.

At the opposite end, the cover 32 is provided with ventilation apertures 51. 35

The motor casing 29 includes a partition 52, having a bore 53 for receiving the ball bearings 42-44 and having another bore 54 for receiving a second ball bearing comprising the races 55, 56 and balls 57. The flexible oil sealing member 40 58 of cup shape prevents the egress of oil from the gear housing chamber 59 into the motor through the bore 54.

The end plate 51 of the motor supports a gear housing 60 which is provided with an offset boss 45 61 having a bore 62 for receiving a sleeve 63. Sleeve 63 has an inwardly extending flange 64 forming a socket 65 for the self-aligning ball bearing, comprising the races 66, 67 and balls 68. An oil seal is preferably provided for preventing 50 leakage of lubricant from the lower end of the gear housing 60 out of the oil seal member, comprising a threaded annular member 69 which is adapted to be threaded into the sleeve 63 and which is provided with a radially inwardly extending flange 70.

55 A flexible packing, such as a leather annulus having a cylindrical flange 71, and a radial flange 72, is secured in the annular member 69, and the radial flange is clamped in place by an annular ring 73.

A garter spring 74 extends about the cylindrical flange 71 and urges it into engagement with an enlarged cylindrical portion 75 on the drive shaft 76. The garter spring is confined in place by a 65 second angular ring 77 and endless coil spring about the cylindrical leather flange which tends to seal the space between the shaft and the housing 60 against the egress of lubricant.

The armature shaft 40 projects out of the 70 motor into the chamber 59 of gear housing 60, where it is preferably provided with a helicoidal pinion 78 which meshes with a similar helicoidal gear 79 carried by drive shaft 76.

The gear ratio is particularly adapted to drive 75

the drive shaft 76 at such a rotative speed that the grinding wheels of predetermined size are driven at a predetermined speed.

It has been found that in order to obtain a proper grinding action with grinding wheels of this type, the wheel must have a minimum speed of 3,500 linear feet per minute, and a maximum of 6,000 linear feet per minute, at the grinding surface. The electric motor, for example, may have a speed of 3,600 revolutions per minute, and in order to provide for grinding wheels of the various predetermined sizes, I prefer to provide a 6,000 R. P. M. driver and a 9,000 R. P. M. driver, the latter being used for smaller wheels.

15 The gears 78, 79 are adapted to step up the speed of the drive shaft 76 over that of the motor shaft 40 to a speed appropriate for carrying out the present methods.

The drive shaft 76 is also preferably formed 20 with an annular shoulder 80 and with a reduced threaded portion 81 for receiving the connection sleeve 82.

25 The sleeve 82 has a threaded bore 83 for receiving the reduced end 81 of the drive shaft, and the sleeve is provided with a frusto-conical or tapered bore 84 for receiving the driven end of the tool holder shaft, which is of complementary shape.

30 Sleeve 82 is also provided with a pair of grooves or slots 85 extending longitudinally into the end of the sleeve and located diametrically opposite to each other, having the grooves 85 substantially semi-circular at 86 to receive the rounded pin 87 carried by the tapered end 88 of 35 the tool holder shaft.

The motor driver 20 is provided at its upper end with a metal handle 89 having apertures 90, 91, below the grip for receiving the fingers, and the handle is provided with a switch actuating member 92 pivotally mounted at 93.

40 The handle 89 contains a snap switch actuated by the lever 92, and is provided with apertures 94 for passing the conductors leading to the switch 95 and leading out of the rubber covered conductor cable 96.

45 The tubular rubber member or hose 97 is secured between the halves of the handle 89 by means of a metal clamping ring 98 which clamps the hose against the cable 96, the ring being disposed in a groove in the handle and secured in place in the handle when the halves of the handle are secured together by the bolts 99. The tubular rubber member 97 prevents a break in the cable where the cable emerges from the handle, and 50 also serves to anchor the cable by the clamping engagement of the rubber of the tube against the cable 96 without injuring the cable.

55 Referring to Fig. 3, this is a vertical sectional view through the tool holder. The pilot 23 is provided with a substantially cylindrical upper part 100, which may be provided with an aperture 101 to receive a pin for manipulating the pilot and shoving it in or pulling it out of wedging engagement with the guide 26.

60 The tool holder 21 is also provided with a tubular metal member 102 having an elongated and accurately machined bore 103 for slidably and rotatably receiving the cylindrical portion 100 of the pilot 23.

65 The tubular member 102 is preferably provided with the reduced end portions 104, 105, each of which is slightly tapered to effect a close frictional fit with the inner race rings 106, 107 of the self-aligning ball bearings. The ball bearings 70 also comprise the balls 108, 109, and the outer

race rings 110, 111. Each of the outer race rings is preferably spun over at one end and at the inner corner 112 to secure an oil seal ring 113 to the bearing. Appropriate packings 114 prevent the lubricant from leaking out of the bearings beyond the oil seal 113.

75 Metal plates 115, 116 slidably mounted on the tubular member 102 are located below the upper ball bearing and above the lower ball bearing, to confine the lubricant between the races. As 10 lubricant is not required in the annular space 117, a spacer sleeve 118 is located in the tool holder casing 119 between the plates 115, 116 to hold the plates in proper position against the ball bearings.

15 The tool holder casing 119 comprises a tubular metal member, such as a steel member, which is provided with a cylindrical bore 120 adapted to receive the outer races 110, 111 and the spacer sleeve 118.

20 The lower end of the tool holder casing 119 is provided with an annular inwardly extending flange 121 forming an annular shoulder 122 against which the lower ball bearing rests, and the lower end of the tool holder casing 119 is 25 provided with a reduced tubular boss 123 for supporting a grinding wheel. The tubular boss 123 has a bore 124 of sufficient size to provide a clearance between the walls of the bore 124 and the tapered pilot 23, since the tool holder is to be 30 guided on the pilot by the sleeve 102 and the ball bearings at each end of the sleeve.

35 The tubular boss 123 is provided with threads 125 for receiving the threads on the inside of a metal hub 126 which supports the grinding wheel 127 of carborundum or other solid abrasive material.

40 The grinding wheels may comprise either rough stones for cutting or relatively smooth stones for finishing work. In some cases, a single stone 45 of suitable quality and texture may be suitably dressed to accomplish both results, the rough dressing being used for cutting, and the smooth dressing for finishing.

45 The lower end of the tool holder 21 is provided with a flat annular surface 128 which extends at right angles to the axis of the tool holder, and it is also provided with a cylindrical surface 129 serving as a guide for receiving the cylindrical flange 130 on a collar 131.

50 This collar will be called the "dress-grind" collar, and its function and structure will be described in detail hereinafter. The collar comprises the cylindrical flange 130 slidably fitting upon a cylindrical part 129 of the tool holder 55 body 119, and the collar comprises an end plate 132 which tapers in thickness from the left side toward the right, as shown in Fig. 3. The end plate 132 has an enlarged bore 133 which may be threaded so that the "dress-grind" collar can 60 be threaded over the threads 125, but it is loosely supported at the unthreaded part 134 between the threads 125 and the flat end 128 of the tool holder. This arrangement permits the convenient assembly of the collar and the removal 65 of the collar, and it also permits the collar to take its proper position on the end of the tool holder, but the collar does not fall off the tool holder due to the threads 125, and the parts of the tool holder are thus permanently assembled 70 together in such manner that no part is apt to be lost.

75 The grinding wheel 127 comprises the metal hub 126, previously described, and the grinding wheel body of abrasive material, which is pref-

- erably provided with a flat top 135, a cylindrical outer surface 136, and a frusto-conical grinding surface 137. The bottom 138 of the grinding wheel may be flat or take any appropriate shape.
- 5 The cylindrical surface 136 of the grinding wheel is merely present on account of a desire to make the grinding wheel of sufficient thickness so that it may be dressed and used over again for a longer period of time until the stone becomes 10 too thin. As the stone is dressed and used up, the length of the cylindrical surface 136 will diminish, and the stone will become thinner in a vertical direction.
- 15 On the small stones it is unnecessary to provide a guard, as the speed at which the stones are rotated is not sufficient to cause any danger, but, if desired, a guard may be provided on all stones, and particularly upon the stones of larger diameter.
- 20 The guard comprises a stamped steel cup having a flat end portion 139 and having a downwardly extending cylindrical border flange 140 encasing the end and a part of the periphery of the stone. The guard may be secured to the hub 126 by spinning over the upper edge of the hub outside the body of the guard.
- 25 A fiber washer 141 is preferably interposed between the "dress-grind" collar 131 and the end of the tool holder so as to facilitate the unscrewing of the grinding wheel from the tool holder, as the metal surfaces otherwise become screwed together so tightly that difficulty is encountered in taking the grinding wheel off again.
- 30 The complete assembly preferably includes a helical coil spring 142 which is interposed between the upper end of the valve stem guide 143 and the lower end of the tool holder.
- 35 It was found that the friction of the tubular boss 123 against the coil spring 142 at the high rates of speed used was so great as to heat the spring and draw the temper from the spring and also melt the sulphur in the grinding wheel. In order to prevent this friction, the tool holder is 40 preferably provided with a thrust sleeve 144 having a bore 145 of sufficient size to receive the cylindrical part 103 of the pilot, and having an annular flange 146 engaging the end 147 of the guide sleeve 102. The thrust sleeve 144 is preferably split longitudinally to permit it to be 45 sprung together, and the flange 146 is sufficiently narrow so that when the split end is sprung together it will pass through the bore 124. The flange 146, however, retains the sleeve in the bore 124 when the spring is removed. The thrust sleeve 144 has a clearance with the bore 124 in 50 the tubular boss 123, and the thrust sleeve extends outward beyond the grinding wheel into engagement with a sheet metal cup shaped member 148.
- 55 The cup shaped member 148 provides a seat for the upper end of the spring 142. Springs of various length should be used, depending upon the distance from the end 143 of the valve stem guide to the valve seat 149. For instance, the 60 top of the spring should be about three-fourths to one inch above the valve seat when the tool holder is removed, to provide sufficient compression for lifting the grinding wheel off the seat. Several lifting springs of different lengths are 65 included as regular equipment.
- 70 In the operation of the device, the pilot stem 23 is, of course, fixed in the guide 26. The guide sleeve 102 is slidably mounted upon the pilot stem and could rotate, but the friction between the 75 guide sleeve 102 and the pilot is greater than the

friction between the inner and outer races of the ball bearings. Therefore, the guide sleeve 102 does not rotate.

There is no friction between the grinding wheel and the spring when the thrust sleeve 144 is utilized. The heating of the spring is thereby avoided and the temper of the spring is not drawn.

Referring to the "dress-grind" collar 131, and referring to Figs. 4 and 5, it will be noted that one side of the collar bears the notation "dress" 10 on the cylindrical flange 130, while the other side of the collar bears the notation "grind", and the cylindrical casing 119 of the tool holder has a mark and the indicia zero. This indicia is used for setting the collar for the dressing or grinding 15 operations respectively and the theory and operation of these elements will be described in detail hereinafter.

It should also be noted that the threads 125 are sufficiently loose with respect to the hub 126 20 so that the position of the grinding wheel 127 is determined by the tapered thickness of the body 132 of the "dress-grind" collar 131; that is, the plate 132 being thicker at one side than the other, the grinding wheel 127 engages the plate 132 and 25 is secured against the plate by the threads 125 in a tilted position, so that the grinding wheel engages the seat 149 at one side, as shown in Fig. 3, but only comes into close proximity to the seat 30 at the other side of the grinding wheel.

The looseness of the threads 125 permits this tilting of the grinding wheel on the tool holder.

The upper end of the tool holder body 119 is provided with threads 150 which may be right hand threads, and the tool holder cap 151 may 35 be provided with threads 152 in a left hand direction.

Connecting sleeve 153 is provided with complementary threads and threaded into the casing 119 and the cap 151. Connecting sleeve 153 is provided with an inwardly extending collar flange 154 forming a seat for a relatively heavy coil spring 155. At its other end the coil spring 155 is seated against a flat steel plate 156, slidably mounted in a bore 157 in a universal joint sleeve 158. The cap 151 comprises a cylindrical member having an inwardly extending annular flange 159 provided with a bore 160 having a curved surface for engagement with the ball 161. The cap is also adapted to receive the universal joint 50 sleeve 158, which comprises a hardened steel tubular member, having four axially extending slots 162 located ninety degrees apart.

The lower end of the universal joint sleeve 158 is provided with axially extending slots 163 for 55 receiving the axially projecting ridges 164 carried by the connecting sleeve 153. Slots and ridges 163, 164 provide a driving connection between the sleeves 158 and 153. A driving connection is provided between the ball 161 and the 60 sleeve 158 by four transversely outwardly projecting cylindrical steel pins 165 engaging in the slots 162.

The slots 162 are of sufficient length so that the pins 165 may move upward and downward in 65 the slots as the ball 161 rotates in the socket provided in the end of the cap 151. Ball 161 is preferably provided with a threaded bore 166 for receiving the reduced threaded end 167 of the ball 70 shank. The ball shank is tapered at 88 for reception in the drive sleeve of the motor driver, and is provided with a transverse pin 87 to be received in the groove 85 of the motor drive shaft.

The motor driver, therefore, rotates the shank 75

88 and ball 161, and with it sleeve 158, sleeve 153, cap 151, casing 119, and grinding wheel 127.

The guide sleeve 102 and pilot, with the inner races of the ball bearings, do not rotate, and the self-aligning ball bearings provide a very smooth rotating action for the grinding wheel, resulting in a uniform grinding action on all parts of the periphery of the valve seat 149.

As it is practically impossible to hold the motor driver 20 axially above the tool holder 21, the universal joint provided by the ball 161, cap 151, and sleeve 158 permits the driving of the tool holder by the motor driver, although the motor driver is not held in direct axial relation to the tool holder. During the driving, the tool holder is guided by the pilot 23, irrespective of the position of the motor. However, it is found that direct mechanical shocks are transmitted to the grinding wheel 22 (Fig. 1) from the motor 20 on account of the action of the universal joint, unless some form of resilient connection is used, and the compression spring 155 in the universal joint eliminates the shock which would otherwise be caused by the universal joint.

25 The use of this spring gives a smooth drive for the grinding wheel and tool holder and facilitates the grinding and finishing of the valves with greater uniformity and a better finish. The shocks caused by the use of the universal joint 30 are not transmitted to the grinding wheel when the spring 155 is utilized, but are absorbed by the spring.

35 Referring to Fig. 4, this shows the tool holder and grinding wheel in the grinding position, and 33 the "dress-grind" collar 131 has been turned so that the word "grind" appears under the mark zero.

The right side of the grinding wheel is accomplishing the grinding action, as evidenced by the 40 dark mark 168 on the frusto-conical surface of the grinding wheel, and the grinding wheel 22 does not come into contact with the valve seat at the side 169, as shown by the space between the wheel and the seat at 169, this clearance being, however, exaggerated for the purpose of 45 illustration. The grinding wheel is, however, sufficiently close to the seat so that the irregular abrasive formations on the wheel cause currents of air which blow off the grindings, and the wheel 50 is self-cleaning. This self-cleaning action enables the grinding of a more finished seat and a more uniform grinding action, because the seat is actually ground to conform to the surface of the grinding wheel and is not marred by the presence 55 of grindings between the wheel and the seat.

The present grinding wheel is preferably dressed apart from the valve seat 149 so that the abrasive which is dressed off the wheel does not fall on the valve seat. For this purpose I prefer to provide a dressing tool, a part of which is shown in elevation in Fig. 5. The dressing tool comprises a supporting base 170 having a flat bottom upon which the dressing tool stands, and the base slidably supports upon a guide lever 180 a plunger 202 carrying an adjustable screw 220 which supports a diamond or other hard cutting member 221. The guide 180 is mounted for pivotal movement with respect to the base 170, and thus the plunger 202 may be made to move along the element of a cone of any angularity. The base 170 supports a dressing pilot 224, the upper portion of which is of substantially the same shape and size as the upper portion 100 of the pilot 23.

At its lower end the dressing pilot 224 is provided with an enlarged cylindrical portion 225 and with a reduced threaded portion 226 which is threaded into the bore 223. The cylindrical portion 225 is adapted to slidably receive a tubular supporting member. The upper end is provided with an inwardly extending radial flange 228 and a bore 229. The bore 229 is adapted to receive the dressing pilot 224, and the tubular member 221 is adjustably mounted on the cylindrical part 225 to support the grinding wheel 22 at the desired height.

For this purpose, the sleeve 227 is provided with a spiral slot 230 which engages the complementary end 231 of a threaded screw bolt 232 having a knurled head 233. The screw bolt 232 is adjustably supported in a threaded bore 234 in a standard 235, the lower reduced end 236 of which is mounted in a bore 231. The standard 235 is secured in place by a set screw 238. A washer 239 is interposed between the hub of the grinding wheel and the end 228 of the supporting sleeve 227 to positively prevent engagement of the grinding wheel with the sleeve 227 and permit the grinding wheel to rotate more freely. This washer should be oiled frequently so as to permit the grinding wheel to rotate freely during the dressing operation.

An understanding of the mode of dressing the grinding wheel is necessary to an understanding of the operation of the grinding wheel, and the manipulation of the dressing tool is illustrated in Figs. 5 and 6. The supporting sleeve 227 is lifted manually by rotating the sleeve, and secured in place by means of the set screw 233 35 engaging in spiral slot 230, with the grinding wheel 22 at the proper height. The grinding wheel 22 is, of course, mounted on the tool holder 21 and adapted to rotate with the tool holder on the dressing pilot 224.

40 The motor driver 20 is again used to drive the grinding wheel at a proper speed during the dressing operation. The diamond supporting sleeve is adjusted so that when the plunger 202 is pushed downward the diamond 221 will engage 45 the grinding wheel 22 and take a very light cut off the surface of the grinding wheel. In order to provide a surface on the grinding wheel which is desirable for fast cutting, the plunger 202 should be pushed down rapidly, but in order to 50 provide a relatively smooth finish on the grinding wheel for finishing, the plunger 202 should be pushed down very slowly while the grinding wheel is rotated by the motor driver 20.

55 Referring to Figs. 4 and 5, these figures illustrate the action of the grinding wheel during the grinding and dressing operations respectively. It has already been explained that the grinding wheel may be supported on the tool holder 21, with its frusto-conical surfaces slightly tilted 60 with respect to the axis of the tool holder, which, of course, also corresponds to the axis of the pilot.

When the grinding wheel 22 is placed upon the tool holder 21 for a dressing operation, the 65 "dress-grind" collar should be turned to the position of Fig. 5, and the grinding wheel 22 threaded home upon the tubular lug 123. The dressing operation is then carried out, as previously described, on the apparatus of Fig. 5, and the 70 frusto-conical surface 137 of the grinding wheel will be made accurately frusto-conical as indicated by the lines 239, 240, drawn from the axis of the dressing pilot. Even though the grinding wheel has its upper flat surface 127 tilted 75

with respect to the axis of the tool holder 21, the surface 137 which is produced by the use of the diamond dressing tool is accurately frusto-conical because the diamond dressing tool is moved along an element of a cone, the axis of which is the axis of the dressing pilot, and the body of the stone is rotated about the axis of the dressing pilot.

The surface 137 is, therefore, accurately frusto-conical, and whether it is relatively rough for fast cutting or relatively smooth for finishing work, will depend upon the manipulation of the dressing plunger. When the dressing plunger is moved down fast during the rotation of the grinding wheel, it may be assumed that the diamond will cut off a part of the grinding wheel surface corresponding to a spiral path, and it might leave parts of the abrasive surface between this spiral path. When the diamond supporting plunger is pushed down slowly during the fast rotation of the grinding wheel, and care is taken that the diamond strikes every part of the grinding surface of the grinding wheel, this surface will be dressed to a substantially smooth frusto-conical finish, as the diamond will have an opportunity to take off all parts of the abrasive surface which it can touch.

When the wheel is to be used for grinding, the grinding wheel 22 and tool holder 21 are removed from the dressing tool, and the "dress-grind" collar 131 is loosened by turning the grinding wheel 22 in a counterclockwise direction and loosening its hub 126 on the threads 125. The "dress-grind" collar is turned one-hundred and eighty degrees from the position of Fig. 5 to that of Fig. 4, until the word "grind" is under the pointer bearing the indicia zero.

Referring to Fig. 5, it will be observed that the thick part 241 of the "dress-grind" collar 131 is located at the left side, and referring to Fig. 4 it will be noted that the thick part 241 of the "dress-grind" collar is located at the right side when the stone is in position for grinding.

In other words, the thickness of the plate between the grinding wheel and the end of the tool holder tapers from left to right in Fig. 5 and from right to left in Fig. 4. If the grinding wheel is tilted upward toward the right in Fig. 5, it will be tilted downward toward the right in Fig. 4. As a result of this, the side of the grinding wheel which is toward the right in Fig. 4 comes in contact with the valve seat, but the side 169 of the grinding wheel in Fig. 4 does not engage the valve seat.

Referring to Fig. 6 the angular relation of the parts is best illustrated by the diagram shown between the grinding wheel and the valve. It should be understood that the proportions of the taper on the spacing plate of the "dress-grind" collar may be varied, and I do not wish to limit myself to any particular taper. This taper is preferably made such that the grinding wheel engages only at one side over substantially one-third of the grinding periphery of the wheel, and the taper is preferably such that the other part of the grinding wheel is located in close proximity to the seat so as to effect a cleaning action by virtue of its proximity and by virtue of the air current caused by such proximity.

For example, in one embodiment of the invention the taper in the spacing plate of the "dress-grind" collar is such that the angle between the upper and lower surfaces of the "dress-grind" collar diverges two-tenths of a degree from the parallel. This divergence is exaggerated in the

diagram shown in Fig. 6. The grinding wheel would, therefore, be tilted two-tenths of a degree toward the left in Fig. 5 and two-tenths of a degree toward the right in Fig. 4; the change in tilt of the grinding wheel from the "dress" position to the "grind" position would be the sum of these two angles, or four-tenths of one degree, or approximately one-half degree.

In other embodiments of the invention, the tilt may amount to several degrees, but it is preferred to keep the tilt as low as possible in order to keep the non-contacting parts of the grinding wheel in close proximity to the surface of the valve. The minimum of tilt permissible is that which accomplishes a suitable dispersement of the cuttings and self-cleaning of the grinding wheel.

Since the grinding wheel is tilted on the tool holder between the time when the wheel is dressed and the wheel is used for grinding, it will be observed that if the dressing tool had its angular markings for any particular angle so disposed that the plunger would move at that angle to the dressing pilot, the angularity of the grinding wheel would not be correct when it is later tilted on the tool holder. In other words, if the diamond supporting plunger were accurately held at forty-five degrees, and the grinding wheel 22 were tilted a half degree to the left, in Fig. 5, then the angularity of the frusto-conical surface 137 would be forty-five degrees and one-half instead of forty-five degrees.

In a similar manner, if the tilt amounted to three degrees toward the left, the angularity of the tool would be forty-eight degrees, whereas a forty-five degree grinding action is desired.

In order to compensate for this action, the markings on the dressing tool of forty-five degrees are preferably not located to hold the plunger at exactly forty-five degrees to the dressing pilot. Each of the angular degree markings is located to hold the dressing diamond plunger at a predetermined angle which will so dress the grinding wheel that the grinding wheel will produce a finished seat of the predetermined angularity desired.

The grinding wheel is not dressed at the angularity desired for the seat, but at such an angularity that when the grinding wheel is tilted that element of the grinding wheel which engages the seat 149 at the right side in Fig. 4 is located at the angle desired.

The dressing tool is thereby adapted to compensate by means of its adjustments and indications for the tilt which is later accomplished by means of the "dress-grind" collar in the grinding operation. The fact that this "dress-grind" collar also may tilt the grinding wheel in the opposite direction prior to the dressing action does not affect the accuracy of the dressing of the wheel, but merely makes the tilt twice as much as could otherwise be accomplished, since the wheel is moved from a position where it is tilted toward the left to a position where it is tilted toward the right.

The method of finishing valve seats or reconstructing valve seats may be carried out by the apparatus described, and is preferably practiced as follows:

A recess is first cut in the seat of the valve in the engine block, the recess being adapted to receive a new valve seat ring of tungsten steel, stellite, or some other hardened alloy better

adapted to withstand the heat and impact to which valve seats are now subjected.

The ring is secured in place by close frictional engagement with the walls of the recess or by spinning over the metal of the engine block above the ring. The tool holder may then be provided with a rough grinding wheel which is placed upon the tool holder with the "dress-grind" collar in the dressing position of Fig. 5.

10 The tool holder and grinding wheel are placed upon the dressing pilot and the tool holder is rotated at a high rate of speed within the range specified, while the diamond dressing tool is moved across the face of the grinding wheel in 15 a direction which corresponds to the angle of the valve seat desired, plus or minus the amount of tilt caused by the "dress-grind" collar. If the same stone is to be used for both the dressing and grinding operations, the diamond is moved quickly across the surface of the grinding wheel to produce a relatively rough and fast cutting wheel. The wheel is then loosened from the tool holder, and the "dress-grind" spacing collar turned one-hundred and eighty degrees, after which the wheel 25 is again tightened on the tool holder and, by virtue of the taper of the spacing plate between the grinding wheel and the tool holder end, the wheel has been tilted a predetermined number of degrees equal to the degrees for which the dressing 30 tool is compensated.

The tool holder is then placed upon the pilot, which has previously been fixedly secured in the valve stem guide in centered relation, and the grinding wheel is supported above the valve seat 35 by means of the compression spring. The motor driver is applied to the upper end of the tool holder, and while the motor is operating at a high rate of speed within the range described the motor and tool holder are pressed down lightly until the grinding wheel engages the seat.

The grinding wheel should not be pressed so hard that the speed of the wheel and the motor is slowed up, but a very light pressure should be used, and as the grinding wheel rotates, the tool 40 holder, wheel and motor should be moved up and down frequently in the same manner as that used in lapping in a valve. The grinding wheel will then come into initial engagement with the seat at different points rotatively of the seat, and 45 the random engagement between the grinding wheel and the seat will give a more uniform action and permit more finished grinding of the seat than a continuous grinding action. The rotation of the grinding wheel tilted with respect to the seat causes only one side of the wheel 50 to grind the seat, and the other side of the wheel aids in dispersing the cuttings from the seat and the wheel by virtue of its close proximity to the seat.

60 The same grinding wheel may then again be dressed to a finished surface and applied to the seat in the same manner to produce a finished seat, or a relatively smooth stone may be dressed and used in the same manner to produce a finished seat. The fast cutting or rough grinding wheel need only be used where there is a great deal of material to be cut away from the seat, as, for example, when a new valve seat ring is 65 used which does not have a frusto-conical seat 70 formed upon it.

In brief, the method of finishing the seat comprises the rotation of a grinding wheel of frusto-conical form while passing a dressing element across the frusto-conical surface of the grinding 75 wheel at an angle which is equal to the angle

of the seat desired plus or minus a predetermined angular tilt, thereby dressing the wheel to an angularity which does not correspond to that of the seat desired, then tilting the grinding wheel with respect to its axis of rotation and applying the grinding wheel to the seat in such manner that only one side of the grinding wheel touches the seat, the tilt being the predetermined amount for which compensation has been made in the dressing operation.

10 It will thus be observed that I have invented an improved method, an improved grinding tool assembly, an improved tool holder, an improved dressing tool, an improved grinding wheel, and other apparatus for the purpose of grinding 15 valve seats of internal combustion engines.

The present grinding apparatus is admirably adapted to handle valve seats of particularly hard alloys and to produce a finished valve seat without necessity for any hand lapping operations. The grinding action of the tilted wheel is very fast and yet smooth and uniform, as the tilting of the wheel effects a dispersion of the cuttings and prevents the loading or clogging of the wheel so that the ground seat corresponds closely to the shape of the accurately dressed grinding wheel.

The use of the spring mounted universal joint prevents the transmission of shocks from the universal joint and motor to the grinding wheel, 30 and also makes for a smoother grinding action of the wheel.

The present results are all accomplished by means of a very simple type of apparatus, which does not require but a single drive shaft and the 35 valve seat grinder is much more simple than the devices of the prior art, so that it may be brought within the reach of a large number of users.

While I have illustrated a preferred embodiment of my invention, many modifications may 40 be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. In a valve grinding apparatus, the combination of a valve stem pilot with a tool holder 50 adapted to be slidably and rotatably mounted on said pilot and a grinding wheel carried by said tool holder, said grinding wheel being tilted with respect to the axis of rotation of said tool holder whereby said grinding wheel engages the work 55 only at one side, a driving shaft for said tool holder, a universal joint connection between said tool holder and driving shaft, and a spring interposed between said driving shaft and said tool holder for absorbing the shocks caused by said 60 universal joint.

2. In a valve grinding apparatus, the combination of a valve stem pilot with a tool holder adapted to be slidably and rotatably mounted on said pilot and a grinding wheel carried by said 65 tool holder, said grinding wheel being tilted with respect to the axis of rotation of said tool holder whereby said grinding wheel engages the work only at one side, a driving shaft for said tool holder, a universal joint connection between said tool 70 holder and driving shaft, a spring interposed between said driving shaft and said tool holder for absorbing the shocks caused by said universal joint, said tool holder comprising a sleeve non-rotatably supported upon said pilot and anti- 75

- friction bearings between said sleeve and the body of said tool holder for supporting said tool holder for rotation at a high rate of speed.
3. In a valve seat grinding apparatus, the combination of a tool holder with a grinding wheel and means for supporting said grinding wheel fixedly upon said tool holder and with the grinding wheel tilted with respect to the axis of said tool holder, said means comprising a threaded connection and a tapered spacing member interposed between a part of said grinding wheel and said tool holder.
4. In an apparatus for grinding valve seats, the combination of a valve stem pilot with a sleeve slidably mounted on said pilot, a tool holder comprising a casing embracing said sleeve, anti-friction means interposed between said casing and sleeve, a grinding wheel carried by said casing, and resilient means interposed between a valve stem guide and said sleeve for lifting said tool holder and grinding wheel off a valve seat.
5. In an apparatus for grinding valve seats, the combination of a valve stem pilot with a sleeve slidably mounted on said pilot, a tool holder comprising a casing embracing said sleeve, anti-friction means interposed between said casing and sleeve, a grinding wheel carried by said casing, resilient means interposed between a valve stem guide and said sleeve for lifting said tool holder and grinding wheel off a valve seat, and a spacing collar engaging said sleeve about said pilot and extending outward from said casing into engagement with said resilient means.
6. In an apparatus for grinding valve seats, the combination of a valve stem pilot with a sleeve slidably mounted on said pilot, a tool holder comprising a casing embracing said sleeve, anti-friction means interposed between said casing and sleeve, a grinding wheel carried by said casing, resilient means interposed between a valve stem guide and said sleeve for lifting said tool holder and grinding wheel off a valve seat, and a spacing collar engaging said sleeve about said pilot and extending outward from said casing into engagement with said resilient means, said spacing collar having a retaining shoulder at its upper end and being split to permit said shoulder to spring inward for the removal of said spacing collar from said tool holder.
7. In a valve seat grinding apparatus, the combination of a valve stem pilot with a tool holder rotatably and slidably mounted with respect to said pilot, a grinding wheel carried by the end of said tool holder and positioned to engage a valve seat, and a tapered spacing member interposed between said grinding wheel and said tool holder to tilt said grinding wheel with respect to said tool holder.
8. In a valve seat grinding apparatus, the combination of a valve stem pilot with a tool holder rotatably and slidably mounted with respect to said pilot, a grinding wheel carried by the end
- of said tool holder and positioned to engage a valve seat, and a tapered spacing member interposed between said grinding wheel and said tool holder to tilt said grinding wheel with respect to said tool holder, said spacing member comprising a collar having a cylindrical flange embracing said tool holder and indicia carried by said tool holder for indicating predetermined positions of the collar for dressing and grinding operations.
9. In a valve seat grinding apparatus, the combination of a tool holder with a rotatably mounted spacing member carried by the lower end of said tool holder, said tool holder having a reduced threaded portion passing through said spacing member, and said spacing member having an enlarged aperture, said spacing member being of greater thickness at one side than the other side, and a grinding wheel carried by the reduced threaded end of said tool holder, said grinding wheel having a threaded bore loosely fitting said threaded end whereby said grinding wheel may be tilted on said tool holder when threaded home, due to the different thicknesses of the parts of said spacing member.
10. In a valve seat grinder, the combination of a pilot adapted to be fixedly mounted in a valve stem guide, said pilot having an upper cylindrical portion, a tool holder slidably and rotatably mounted on said cylindrical portion and guided thereby, a grinding wheel carried by said tool holder for engaging a valve seat, said tool holder having an aperture in its upper end for receiving a driving member, complementary non-circular formations on said driving member and said tool holder at said upper end whereby a limited universal joint connection is formed between said driving member and said tool holder, and a spring located in said tool holder below said driving member and engaging said driving member for absorbing the shocks caused by said driving member on said tool holder.
11. In a valve seat grinding apparatus, a tool holder comprising a body having a cylindrical part adapted to slidably engage a valve stem pilot, a grinding tool carried by said tool holder and adapted to be rotated and reciprocated on said pilot by said tool holder, said tool holder having a drive socket in its upper end, a driving member having a driving connection with said socket, and a resilient member located in said socket and engaging said driving member to absorb shocks and to permit said grinder to ride upward over grindings between the grinding wheel face and the valve seat, said tool holder socket and driving member connection comprising engaging non-circular formations in said socket and on said driving member and having sufficient clearance for a limited universal movement between said driving member and said tool holder at said socket.

FRANS O. ALBERTSON.
